UNITED STATES PATENT OFFICE.

HERBERT A. WORTH, OF LONG BEACH, CALIFORNIA, ASSIGNOR OF ONE-HALF TO JOHN PHILIP CRELLEY AND VERNON L. BOOK, BOTH OF LONG BEACH, CALIFORNIA.

TOOTH EXERCISER.

Application filed May 14, 1924. Serial No. 713,192.

This invention relates to tooth exercisers, and it has as one of its objects the provision of a device for strengthening the teeth, for increasing the security of the teeth in their sockets, and for stimulating the circulation of blood in the gums whereby the teeth are better nourished.

With the foregoing objects in view, together with such other objects and advantages as may subsequently appear, this invention consists in the construction and arrangement of parts hereinafter described and claimed and illustrated in the accompanying drawings, in which:

15 Figure 1 is a view of a man employing my device to exercise his teeth,

Fig. 2 is a plan view of my device which includes hinged members, this view showing in dotted lines the position of one of the 20 hinged members when swung back from the member to which it is hinged, and

Fig. 3 is a section taken on the line 3—3 of Fig. 2.

Referring to the drawings for a more detailed description thereof, the numeral 5 indicates generally my tooth exerciser, which comprises an upper member 6 and a lower member 7. These two members have the configuration similar to a set of teeth and are hinged to each other. A channel-shaped clamp 9 is provided for clamping the members 6 and 7 to each other and comprises a web 10 adapted to fit against the edges of the members 6 and 7 respectively. Flanges 11 are formed integral with the web 10 and are adapted to engage respectively the upper surface of the member 6 and the lower surface of the member 7. The upper flange 11 is pivoted to the hinged member 6 by means of a pin 12 which is peened on its tail end. The members 6 and 7 are provided with opposing slots and these slots each have a configuration similar to that of a set of teeth.

45 Each of the members 6 and 7 carries a resilient material 13, such, for example, as a body of rubber, which extends through the slot provided for the purpose. Each body of material 13 is provided at one end with 50 opposing flanges 14 which contact with the inner face of the member by which it is carried. The material 13 carried by the

member 6 extends above the upper surface of the member 6 and the material 13 carried by the member 7 extends below the lower 55 surface of the member 7. The bodies of material 13 are intended to be held tightly between the teeth which bite on the material 13.

The device of my invention includes a 60 handle 15 secured to a shank 16 which is affixed to the upper hinged member 6.

In using my device, the members 6 and 7 are placed in the mouth and are positioned so that the body of material 13 in the hinged 65 member 7 rests on the lower set of teeth. The upper set of teeth is then brought into engagement with the body of material 13 carried by the upper hinged member 6. The bodies of material 13 are then held 70 rigidly between both sets of teeth by a biting force. The device is then held by the handle 15 and force is exerted on the device by pushing inwardly, pulling outwardly, 75 pushing upwardly, and pulling downwardly, as indicated by the arrows in Fig. 1. This action serves to accomplish the objects of this invention.

This invention has been described, but modifications thereof may be devised without departing from the spirit thereof, and it is to be understood that such modifications come within the scope of this invention.

What is claimed is:

1. A tooth exerciser comprising an upper member, a lower member, said members being hingedly connected to each other, and adapted to be inserted in the mouth and resilient material carried by each of said members and formed to be engaged by a set of teeth, said resilient material projecting above said upper member and below said lower member and being readily removable from said members.

2. A tooth exerciser comprising an upper member, a lower member, said members being hingedly connected to each other, and adapted to be inserted in the mouth, resilient material carried by each of said members and formed to be engaged by a set of teeth, said resilient material being readily removable and projecting above said upper member and below said lower member, and

means for clamping said members to each other.

3. A tooth exerciser comprising an upper member, a lower member, said members being hingedly connected to each other, and adapted to be inserted in the mouth, removable resilient material carried by each of said members and formed to be engaged

by a set of teeth, said resilient material projecting above said upper member and below 10 said lower member, means for clamping said members to each other, and a handle secured to one of said members.

In testimony whereof I have signed my name to this specification.

HERBERT A. WORTH.
